UNITED STATES PATENT OFFICE.

CHARLES M. SULLIVAN, OF MARION, INDIANA, ASSIGNOR OF ONE-HALF TO LUTHER L. BOND,
OF MARION, INDIANA.

CAR-REPLACER.

No. 903,115.

Specification of Letters Patent.

Patented Nov. 3, 1908.

Application filed May 25, 1908. Serial No. 494,814.

To all whom it may concern:

Be it known that I, CHARLES M. SULLIVAN, a citizen of the United States, residing at Marion, in the county of Grant and State 5 of Indiana, have invented certain new and useful Improvements in Car-Replacers; and I do declare the following to be a full, clear, and exact description of the invention, such as will enable others skilled in the art to 10 which it appertains to make and use the same.

My invention relates to improvements in car replacers.

It has for its object to provide for readily replacing a derailed car upon the rails; and to provide for readily applying the car replacer for use in connection with the track rails; to also effect the aforesaid purpose with the minimum additional aid in replacing 20 the derailed car, and to simplify the construction and operation of the parts.

With these and other objects in view, the invention consists of certain novel features of construction, combination and arrangement of parts as will be described and particularly pointed out in the appended claims.

In the accompanying drawings, illustrating the preferred embodiment of my invention, Figure 1 is a plan view of one member 25 of my car replacer; Fig. 2 is an elevation thereof, viewing the same from the opposed rail side thereof; Fig. 3 is a bottom plan view of the same, with the rail clamping arms also shown in dotted lines; Fig. 4 is a 30 plan view, of one of the car replacer members adjusted to the rail for use; Fig. 5 is a similar view with the clamping arms disengaged from the rail; Figs. 6 and 7 are end views of the two members of the car replacer 35 as arranged in connection with the rails for use; and Fig. 8 is a vertical sectional view of one of the car replacer members produced 40 on the line a—a of Fig. 2.

In carrying out my invention, I provide 45 two car replacer members, 1, 1^a, the same being of duplicate structural outline, but one being, however, of somewhat greater height than the other, as is common in contriving devices for effecting the replacing of a derailed car upon the rails. As each car replacer, as above described, is substantially a 50 duplicate of the other, the following description will be confined to a single member.

Said car replacer member is preferably

constructed of a hollow or shell-like metal 55 piece, with its base preferably of frame-like outline, as seen in Fig. 3. The car replacer member has an upper portion 2, formed with two inclines, sloping from its center toward each end, at which central portion is 60 applied a laterally inclined plate or member, 3, riveted or otherwise suitably secured in place, said laterally inclined latter member having its lower edge in one replacer member slightly below the top edge of one rail, 65 the corresponding laterally inclined member 3 of the opposite car replacer member having its lower edge about in the same horizontal alinement with the tread or upper surface of the opposite rail, as shown in 70 Figs. 6 and 7, the purpose of which arrangement is to conduct the car toward the rails as it reaches the eminence of the car replacer members. Said car replacer member has its inner lateral surface also inclined from each 75 end centrally of the latter and converging with the inclined upper surface thereof. This laterally inclined surface or edge is provided with an upstanding flange 4 extending from alining corner edges of said replacer member to aid in effecting the car replacing operation, as the wheels of the car travel up the incline of the replacer member.

Arms or bars, 6, are pivotally connected 80 to the underside of the car replacer member by means of pivot bolts, 12, said arms being arranged near the ends of said replacer member and having preferably serrated pivoted jaws, 7, 8, the action of which jaws, it will be noted, when the replacer member is applied 85 to the track, as indicated in Figs. 4 and 5, is to grip or clamp the base or flange of the rail (more particularly disclosed by one of said views) as said replacer member is moved endwise or manually, and thus provide 90 for substantially securing said replacer member automatically in position upon the rail base. It will be noted that the replacer member has its inner longitudinal corner edges undercut or recessed, as at 11, in order 95 to provide for snugly receiving the rail base and thus provide for disposing the replacer member contiguous to the rail, and also to enable the rail base to afford a staple bearing for said replacer member.

It will be seen from the foregoing described construction of parts that a practical, simple and effective car replacer is obtained

and whereby the operation of replacing a derailed car may be effected with facility and with the minimum number of attendants and the least manual assistance.

5 From the foregoing description, taken in connection with the accompanying drawings, the construction and operation of the invention will be readily understood without requiring a more extended explanation.

10 Various changes in the form, proportion and the minor details of construction may be resorted to without departing from the principle or sacrificing any of the advantages of the invention as disclosed in the appended 15 claims.

Having thus described my invention, what I claim as new and desire to secure by Letters-Patent, is:

1. A device of the character described em-

bracing a car replacer member equipped 20 with pivoted arms, having pivoted jaws.

2. A device of the character described comprising a car replacer member having oppositely straight inclined upper surfaces and laterally inclined surfaces, said inclined surfaces having a common point of convergence, a laterally inclined member arranged at said common point of convergence, and pivoted arms connected to said replacer member, said arms having pivoted serrated jaws adapted 25 to engage the rail base.

In testimony whereof I have hereunto set my hand in presence of two subscribing witnesses.

CHARLES M. SULLIVAN.
